UNITED STATES PATENT OFFICE.

THOMAS SUTERS, OF ILION, NEW YORK, ASSIGNOR TO LIBRARY BUREAU, OF BOSTON,
MASSACHUSETTS, A CORPORATION OF NEW JERSEY.

LOCKING-CLAMP.

1,053,328

Specification of Letters Patent. Patented Feb. 18, 1913.

Application filed November 11, 1911. Serial No. 659,714.

To all whom it may concern:

Be it known that I, THOMAS SUTERS, a citizen of the United States, and resident of Ilion, in the county of Herkimer and State of New York, have invented new and useful Improvements in Locking-Clamps, of which the following is a specification.

This invention relates to locking clamps to hold two frame members together, and it is particularly designed for use in museum or display cabinets and cases and similar structures, wherein the marginal frames of panels or walls are juxtaposed, and it is desired to lock them together by a clamp which shall embrace both frames, and which may be readily unlocked if it is desired to separate the frames, as where one of the frames and its panel constitutes the door of the cabinet. In cabinets of this sort, in which the walls are usually made up each as a unit consisting of a glass panel and a metal marginal frame, and in which several such units are fastened together to form the cabinet or case, ordinary door locks or sliding bolt-rods for that framed panel which is used as the door, are unsatisfactory for the reason that any slight imperfection in the fitting of the parts, or warping of the structure will prevent such locks from operating, or from holding the door tightly closed upon its seat. Furthermore, ordinary locking devices have to be incorporated into the frames, which must therefore be specially prepared for receiving the locks. With the use of my invention two juxtaposed frames may be firmly and tightly locked together notwithstanding any slight distortion or lack of fit in the structure, and the device may be applied to the frames without any previous preparation or alteration in the structure of the frames whatsoever.

The device may also be used if desired as a clamp for securing together the juxtaposed frames of walls or panels which are intended to be permanently fastened, as well as for fastening a movable door frame to a fixed frame. When so used, it presents marked advantages over spring clips heretofore used in structures of this sort, since it is more positive in its action, and also prevents the accidental or intentional separation or loosening of the cabinet walls by unauthorized persons.

In the accompanying drawings, which illustrate certain embodiments of the inven-

tion,—Figure 1 is a perspective view of my preferred form of locking clamp in operative position on the corner of a cabinet or case; Fig. 2 is a horizontal, sectional view through said clamp and corner of the cabinet on a plane coincident with the top of the pivoted jaw presently to be described; Fig. 3 is a vertical section on line 3—3 of Fig. 2, the pivoted plate being shown in elevation; Fig. 4 is a top view of a modified form of clamp containing my invention; Fig. 5 is a front elevation of said modified form of clamp; Fig. 6 is a rear elevation of said modified form of clamp; and Fig. 7 is a section on line 7—7 of Fig. 6.

Referring first to the form of the invention illustrated in Figs. 1, 2 and 3; A, A, represent metal marginal frame members, each having a mitered or beveled bearing surface adapted to form a tight joint with the corresponding surface of the other frame when the two frames are juxtaposed as shown in Figs. 1 and 2, and each having a channel in which the edge of a panel B is held. These frames and panels constitute no part of my invention.

The body of the clamp consists of a body plate shaped to fit the outer surfaces of the juxtaposed frame members A, A. As herein shown said frame members are at right angles with each other and the body plate of the clamp is therefore composed of the two angularly arranged wings a and a'. The free edge of the wing a is provided with an inwardly turned fixed jaw a² to engage one of the frame members A, and the other wing a is cut away or recessed inwardly from its free edge on lines a³, a⁴ and a⁵ (Figs. 1 and 3), and the recess is closed by a filler plate a⁶. The filler plate a⁶ is made with an inwardly turned jaw a⁷, and is pivoted to the body plate within said recess by pins or trunnions a⁸. When in closed position as shown in Fig. 1 and in solid lines in Fig. 2, the jaw a⁷ engages the edge of the frame member opposite to that engaged by jaw a², said jaws holding the two frames A, A, together. When jaw a⁷ is swung open on its pivot as shown in dotted lines in Fig. 2, the jaws are disengaged and the frame members released.

In order securely to lock the jaws in closed position so as positively to hold the frame members clamped together, the filler plate a⁶ is provided with a lock which may

be of ordinary construction, only the bolt of the lock b , and the key hole c , being shown in the drawings. A slot b' is formed in the side of the recess in wing a , opposite the bolt to engage the bolt when the latter is thrown outward by the key. Thus the filler a^3 and jaw a^2 may be positively locked in closed position relatively to the other jaw a^2 , and in that position the opposed jaws a^2 will hold the frame members together, and the outer surfaces of the filler plate will be smooth and flush with the outer surface of the body plate.

Referring now to the modifications shown in Figs. 4 to 7, the body plate consists of the wing d' and jaw d^2 , like the aforesaid wing a' and jaw a^2 , and the wing d which corresponds with the aforesaid wing a , in that it supports the movable jaw. In this form of the device, the movable jaw d^2 is provided with sliding arms d^4 and d^5 fitted to slide in grooves d^6 and d^7 in wing d . Between said arms is a lock e , which may be of usual construction, secured to the wing d , the bolt of the lock being shown at e' and the key hole at e^2 . The sliding arm d^5 is provided with a recess d^8 into which the lock bolt e' projects to hold the movable jaw d^2 in closed position, when the device is clamped upon the frame members in the same position in which the other clamp is shown in Fig. 1. When the bolt e' is withdrawn the sliding jaw d^2 may be moved outwardly with relation to the opposed jaw d^2 to the position shown in dotted lines in Fig. 4, and in Fig. 5. A stop is provided to limit such outward movement, consisting of a pin g secured to the wing d and working in the slot h in arm d^4 .

I claim:

1. In combination, a pair of juxtaposed marginal frame members, and a locking clamp extending across the faces of said juxtaposed frame members, having two relatively movable jaws adapted when in closed position to engage respectively the opposite outer edges of said frame members, said jaws also adapted to open by a relative movement of separation to disengage the clamp from the frame members, and a lock adapted to lock one of said jaws to the other independently of said frame members positively to hold said jaws against such movement of separation when in closed position.

2. A locking clamp comprising a body plate, a fixed jaw at one edge of said plate, the other edge of said plate having a recess therein, a movable filler in said recess carrying another jaw, said filler closing the recess when in closed position, and a lock adapted positively to lock said filler and its jaw in closed position.

3. A locking clamp comprising a body plate composed of two angularly arranged wings, an inwardly turned fixed jaw at the free edge of one of said wings, the other of said wings having a recess extending inwardly from the free edge thereof, a filler plate in said recess pivoted to said body plate and having an inwardly turned jaw, and a lock adapted positively to lock said filler plate and its jaw in closed position.

Signed by me at Ilion, N. Y. this second day of November, 1911.

THOMAS SUTERS.
